CLAIM

The ornamental design for a golf tee as shown and described.

DESCRIPTION

FIG. 1 is a perspective view of a golf tee, according to a first embodiment.

FIG. 2 is a side elevation view thereof;

FIG. 3 is a top plan view thereof;

FIG. 4 is a bottom view thereof.

FIG. 5 is a perspective view of a golf tee, according to a second embodiment;

FIG. 6 is a side elevation view thereof;

FIG. 7 is a top plan view thereof; and,

FIG. 8 is a bottom view thereof.

The broken lines show portions of the golf tee that form no part of the claimed design.

1 Claim, 8 Drawing Sheets
